Primary Examiner — Paula Allen Greene

(57) **CLAIM**

The ornamental design for a headset for telephones with earphones and microphones combined as shown and described.

DESCRIPTION

1. Headset for telephones with earphones and microphones combined

1.1: Front perspective view

1.2: Back perspective view

1.3: Front view

1.4: Back view

1.5: Left view

1.6: Right view

1.7: Top view

1.8: Bottom view

The dash-dash broken lines in the drawings depict the portions of the headset for telephones with earphones and microphones combined that form no part of the claimed design.

1 Claim, 8 Drawing Sheets
